UNITED STATES PATENT OFFICE.

CHARLES R. BIRDSEY, OF HINSDALE, ILLINOIS, ASSIGNOR TO UNITED STATES GYPSUM COMPANY, OF CHICAGO, ILLINOIS, A CORPORATION OF ILLINOIS.

PLASTER BOARD.

Original application filed January 2, 1920, Serial No. 348,940. Divided and this application filed January 3, 1921. Serial No. 434,649.

To all whom it may concern:

Be it known that I, CHARLES R. BIRDSEY, a citizen of the United States, residing at Hinsdale, in the county of Du Page and 5 State of Illinois, have invented certain new and useful Improvements in Plaster Board (Case B-1), of which the following is a description.

My invention belongs to that general 10 class of devices known as plaster board or the like, and relates particularly to an improved board which will be simple convenient, substantial, durable, satisfactory and efficient, and which may be economically 15 and accurately manufactured. The invention relates particularly to a type of board in which the plaster, plaster Paris or plastic material body is substantially enclosed on one or both opposite edges, as well as the 20 face sides, and which edges may be perfectly formed to conform to a definite specification as to size or angle. Many other objects and advantages of the construction herein shown and described will be obvious 25 to those skilled in the art from the disclosures herein given.

To this end my invention consists in the novel construction, arrangement and combination of parts herein shown and described and more particularly pointed out 30 in the claims.

In the drawings, wherein like reference characters indicate like or corresponding parts,

35 Figure 1 is a sectional view through a portion of a plaster board embodying the invention;

Figure 2 is a perspective view of a portion of the board;

40 It may be mentioned that the present application is a divisional application of my application Ser. No. 348,940 which matured into Patent 1,395,031 on October 25, 1921.

45 Referring to the drawings 1 represents a body of suitable material, as for example plaster, plaster Paris, or any equivalent suitable for the purpose which may preferably be handled in a plastic state and thereafter allowed to set or harden. The 50 body is enclosed between the covering sheets 2 and 3 of suitable covering material, and in this connection it may be mentioned that I have found that paper of the desired

weight or thickness very satisfactory for 55 the purpose. One of the covering sheets, as shown sheet 2, is folded toward the covering sheet 3 so as to enclose the plastic material at the edges of the board. Ordinarily I prefer to score the sheet 2 as indicated at 60 7 so that a perfect corner 5 may be formed, the particular contour of the extreme edge, however, being as desired, and the angle being as preferred. In this type the upturned edge or flange 4 is of a width so 65 that the same will underlie the inner face of the top sheet 3, and the same extend substantially flush with the extreme edge of the cover 3. Generally, the edges 4, which may be turned up as mentioned on one or 70 both sides, will adhere to the plastic body so that it is unnecessary to use additional ingredients or material to secure the same in place. A portion of the material will leak between the extreme edge 6 and the 75 top sheet and the flange or side 4, securely sealing and securing the two together. The board may be produced by any desired method or process and with such machinery as may be suitable for the purpose. The 80 width of the turned up edge or flange portion 4, it being understood that it is immaterial which sheet is provided with the flange, will depend upon the thickness of the body and whether the edge is straight 85 or at angle to the faces of the board, the straight type edge being shown in the drawings.

It will be noted that in this construction, the edge is substantially completely enclosed, and as before mentioned, this may be at one or more sides. If the two sheets are integral and wrapped or folded over one edge, or it is desired to enclose only one edge, then this construction might only be 90 employed at one edge, the opposite edge or edges being different. The resulting product presents a finished and smooth edge and at a perfect desired angle, the board being uniform in width throughout its length. 100 The completed product has many advantages, including increased strength and durability, and an improved appearance. In case of handling, the edges are protected and there is no breaking away nor sifting 105 out or powdering of the body at the edge.

Having thus described my invention, it is obvious that various immaterial modifica-

tions may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

- 10 1. A plaster board of the kind described comprising a body and a covering sheet arranged at each face side thereof, one of said sheets folded over the edge of the board and extending to the opposite face and terminated thereat and underlying the cover sheet at said face.
- 15 2. A plaster board of the kind described comprising a body and a covering sheet arranged at each face side thereof, one of said sheets folded over at opposite edges of the board and extending to the opposite face and terminated thereat and underlying the cover sheet at said face.
- 20 3. A plaster board of the kind described comprising a body and a covering sheet

arranged at each face side thereof, one of said sheets scored and flanged over to enclose the edge of the body and extending to adjacent the opposite face and underlying the cover sheet at said face and terminated thereat, said last cover sheet being of a width to project to the outer face of the flanged portion of the other sheet.

4. A plaster board of the kind described comprising a body and a covering sheet arranged at each face side thereof, one of said sheets folded over at opposite edges of the board to enclose the edge of the body, said folded over edge portions terminating short of the other cover sheet with their extremities underlying the edges of said other cover sheet.

In testimony whereof, I have hereunto signed my name in the presence of two subscribing witnesses.

CHARLES R. BIRDSEY.
